US0D1033030S

(12) **United States Design Patent** (10) **Patent No.:** **US D1,033,030 S**
(45) **Date of Patent:** **** Jul. 2, 2024**

(54) **FOOTWEAR**

(71) Applicant: **Bob Barker Company, Inc.**,
Fuquay-Varina, NC (US)
(72) Inventor: **Jeremy Amidon**, Apex, NC (US)
(73) Assignee: **BOB BARKER COMPANY, INC.**,
Fuquay-Varina, NC (US)
(**) Term: **15 Years**

(21) Appl. No.: **29/816,418**

(22) Filed: **Nov. 22, 2021**

(51) **LOC (14) Cl.** **02-04**
(52) **U.S. Cl.**
USPC **D2/916**

(57) **CLAIM**

The ornamental design for footwear, as shown and described.

DESCRIPTION

FIG. 1 is a top view of footwear.

FIG. 2 is a first side view of the footwear.

FIG. 3 is a second side view of the footwear; and,
FIG. 4 is a bottom view of the footwear.

The dash-dash broken lines in the figure views depict
portions of the footwear that form no part of the claimed
design. The dot-dash broken lines represent the boundaries
of the claimed design and form no part thereof.

1 Claim, 3 Drawing Sheets
